UNITED STATES PATENT OFFICE.

ADOLPH PAULSEN, OF SAN CARLOS, CALIFORNIA.

CASING FOR ARTESIAN WELLS.

Application filed May 17, 1926. Serial No. 109,690.

The present invention relates to improvements in casings or linings for artesian wells. The ordinary casing or lining of an artesian well functions merely as a means for preventing the side wall of the well from collapsing and thereby clogging the well. The casing which is usually in the form of a perforated metallic pipe is wholly exposed to the water of the well with the result that the material of the casing readily 10 rusts and eventually decomposes.

The present type of casing, moreover, does not act to filter the water of the well to the end that when the well is sunk in 15 clay-like earth, as distinguished from gravel, the water delivered by the well is accompanied by an earthy deposit.

Coming now to the present invention, the general object thereof is the provision of a 20 casing adapted to be arranged within an artesian well and to provide a lining for said well and further to provide a means for filtering the water entering the well.

The above and other objects are accomplished by instrumentalities pointed out in 25 the following specification.

The invention is clearly defined in the claims.

A satisfactory embodiment of the invention is illustrated in the accompanying 30 drawings forming part of the specification and in which

Figure 1 is a horizontal cross section of an artesian well showing one form of my invention in use.

Figure 2 is a vertical longitudinal section of the lower portion of a well, together with the form of the invention shown in 35 Figure 1 and appearing partly in side elevation and partly in vertical cross section.

Figure 3 is an enlarged vertical cross sectional detail of one of the units of the casing shown in Figures 1 and 2.

Figure 4 is a detail perspective on an enlarged scale of one of the units complete 45 shown in Figures 1 and 2, together with a fractional part of an additional unit.

Figure 5 is a view similar to Figure 2 of a modified form of the invention.

Figure 6 is a detail plan of a further modified form of casing unit.

Figure 7 is a detail side elevation of the lower end portion of a well and showing

a casing in side elevation and made up of the units shown in Figure 6.

Figure 8 is a face view of the interior of one of the portions of the unit shown in Figure 6.

Figure 9 is a plan view of Figure 8.

Figure 10 is a front elevation of one of the tie rod sections shown in Figure 7.

Figure 11 is a horizontal cross section on the line 11-11 of Figure 7.

Figure 12 is a detail perspective of one of the lowermost tie rod sections, and

Figure 13 is a detail of the connection between the tie rod section shown in Figure 12 and the shoe, showing parts partly in side elevation and vertical cross section.

In Figures 1, 2, 5, 7 and 11, 5 indicates the bore of the well and 6 the wall. In carrying out the present invention in connection with a well extending through soil or clay-like earth, the use of that form of the invention shown in Figures 1 to 3 inclusive is preferable, while the form of the invention shown in Figures 5 and 6 is preferable in connection with a well extending through loose or gravel-like earth; however, the latter two forms of the invention may well be used in connection with earth of a clay-like formation. In its various forms 70 the invention essentially consists of a casing made up of superimposed units which are indicated throughout by *a*. In Figures 1 to 5 inclusive the units are the same for both forms of the invention: whereas in the form shown by Figures 6 to 9 inclusive and Figure 11, the units are constructed somewhat different from the forms shown in Figures 1 to 5. In all forms, each units consists of two sections respectively indicated by 7 and 8, each of said sections being semi-circular in contour and formed of molded plastic material, such as ordinary cement, or 75 a mixture of cement and sand, or, if preferred, each section may be formed of baked clay and glazed or not. In all forms of the invention, the sections 7 and 8 are arranged end to end so as to provide the circular shaped unit *a*, and the lining or casing in all forms is provided by superimposing its units one upon the other so as to extend throughout the depth of the well. 80

9 indicates a plurality of ducts extending vertically through each of the sections 7 and 8

85

and spaced apart for any required distance. The ducts 9 are open-ended and the lower end of each duct communicates with a recess 10 opening through the outer side of 5 the section and formed in the end surface thereof, and the upper end of each duct communicates with a lateral recess 11 which opens through the inner face of the section and formed in the upper end thereof. It 10 is thus to be seen that liquid may flow into the recesses 10 and upwardly through the ducts 9 and into the well through the ducts 11. As shown in Figures 1 to 5 inclusive 15 and Figure 11, the ducts 9 are filled with suitable filtering material such as small pebbles 12 so that the water in flowing into the well works its way through these pebbles which operate in the usual manner to strain or filter the water of any sediment deposited 20 therein. The diameter of each unit is, of course, determined by the diameter of the bore 5 of the well and further by the fact as to whether the unit is to be used as a 25 supplemental casing, as shown in Figure 1, or as the sole casing for the well, as shown in Figures 5 and 7. The height of each unit in any form of the invention may correspond with the heights in the other forms. It has been found in practice that the 30 convenient height is approximately six inches.

In carrying out the invention in connection with the form shown in Figures 1 and 2, an outer perforated metallic casing 13 is employed. This casing is in sections and 35 each section corresponds in length approximately to the combined heights of several of the units *a*. Adjacent sections 14 are connected by an annular tie plate 15 disposed interiorly of the sections and suitably secured thereto as by bolts or rivets as at 16. The lowermost section of the metallic casing is interiorly provided at its lower end portion with an annular shoe 17 which is 40 secured as by bolts or rivets 18 to the said section, said shoe being of metal and having an upwardly and inwardly sloped side 19 which terminates in a flat side 20 extending laterally outward and forming a support for the lowermost unit *a*. The units are so proportioned with respect to the diameter of 45 the section 14 as to provide an intervening space 21 which is filled with filtering material, such as pebbles 22. The lowermost section is assembled with the units *a* after 50 which the upper section is secured in place by the tie plate 15. This assembling is done preparatory to lowering the pair of connected sections into the bore 5. The services of a suitable derrick are employed for 55 hoisting the connected sections and supporting the same during the operation of directing the lowermost section into the bore 5 at a time after the lowermost section has 60 been entered into the bore and before the succeeding section descends into the bore,

the units for the said succeeding section are placed therein, after which a third section is connected to the second and this operation continued until the lowermost section is at the bottom of the well. It is to be noted 70 that in arranging the units of the several sections, the units are so disposed as to provide a break-joint effect as shown in Figures 2 and 4. In these figures it is to be noted that the outlet end portions 11 of the 75 ducts 9 are bridged by the lower sides of the sections immediately thereabove so that the water flowing upwardly through the ducts is directed inwardly and into the bore 80 5 of the well.

In the use of the device shown in Figures 1 and 2, the water from the ground first enters through the openings 23 of the metallic outer casing, filters through the gravel 22, then passes through the ducts and the 85 gravel therein and into the bore 5, all of which is shown by the arrows in Figure 3.

In the form shown in Figure 5, the perforated metallic casing 24 is disposed interiorly of and concentrically with the units *a*. The lower end of casing 24 is connected by screw threads as at 25 to the screw threaded lower end portion of a shoe 26. The casing 24 is, of course, sectional and each section accommodates a plurality of 95 units as pointed out in connection with the form shown in Figures 1 and 2. In connection with the form shown in Figure 5 however, the units *a* are of greater diameter than those shown in Figures 1 and 2, and are of 100 a size to snugly fit within the bore 5 of the well. The use of this form of the invention is preferable in connection with gravel-like 105 formations of soil, although its use is possible with clay-like soil formations.

In connection with the forms shown in Figures 6 to 13 inclusive, the employment of a tubular metallic casing is dispensed with and in its stead tie bars are provided and slight modification made in the construction 110 of the sections of the units. The tie bars are of metal and one is shown in Figures 10 and 12 and indicated by 27. The shoe is indicated by 28, and a fragment shown in Figure 13, and is provided with an annular pocket 29 which is disposed between the outer vertical side wall 30 and the upwardly and inwardly sloping inner side wall 31. The top plate 32 is provided at diametrically opposite points with transverse slots, one of 115 which is shown and indicated by 33. The tie rods extend upwardly from the oppositely disposed slots 33, the lowermost sections 27 of the tie rods being provided at their 120 lower ends with angularly shaped tongues 34. The annular pocket 29 is filled with cement in the operation of forming the pocket. In assembling the parts for insertion into the bore as shown in Figure 7, 125 water is added to the cement 36 which is con-

tained in the pocket 29, or, if desired, the cement may be first mixed and introduced into the pocket prior to bolting the side walls 30 and 31 together as indicated by 35.

5 The tongues 34 are inserted into the slot 33 and embedded into the cement before the same hardens.

In Figures 7 to 13 the tongue 34 of one of the lowermost sections of the tie rods is 10 shown embedded in the concrete 36. It is to be noted that the tie rod sections are relatively thin and rectangular in cross section and the shoulders resulting from the reduced tongues on the lowermost sections bear upon 15 the top plate 32 when the lower sections are arranged vertically after introducing the tongues through the slots and into the cement. The sections 37 and 38 of the lowermost unit in Figure 7 bear upon the top 20 plate 32 of the shoe 28 and the lowermost sections of the tie rods extend upwardly between the adjacent ends of the sections 37 and 38. The length of the lowermost section 25 of the tie rod is equal approximately to the height of three of the units made up of the sections 37 and 38, and the said lowermost sections at points immediately above the lowermost unit are provided with transverse openings 39 for transversely disposed 30 dowels which are adapted to fit into depressions in the end portions of the lower sides of the unit disposed upon the lowermost unit.

35 In Figure 7 I have shown this construction as the same would appear from one side of the well only one of the dowels showing and indicated by 40. With this construction it is to be observed that the lowermost sections of the tie rod operate to tie the shoe and the 40 lowermost tie rod sections together. The dowel 40 also passes through an intermediate tie rod section 41 in Figure 7, and the length of this section corresponds to the length of the lowermost section 27 above the shoe 28,

45 so that the upper end portion of the intermediate section projects above the upper end of the section 27 for a distance equal to the height of one of the units. When a third unit is superimposed upon the second unit 50 as shown in Figure 7, the structure thus far assembled may be suspended by pulling upwardly on the projecting end portions intermediate sections 41 of the tie rod, it being obvious that the dowel 40 connects the sections 27 and 41 together. A pair of dowels, 55 one of which is shown in Figure 7 and indicated by 42' are disposed in depressions in the lower faces of the sections of the third unit shown in Figure 7 in the manner described for the dowels 40, and these dowels 42' pass through a lining openings in the upper portion of the lowermost tie rod section 27 and in the intermediate portion of the intermediate tie rod section 41 and 60 through the lower end portion of a third tie

rod section 43, and thereby operate to tie the three sections of the tie rod one to the other as shown in Figures 7 and 11. The lengths of the intermediate and third tie rod sections correspond so that when a fourth unit is 70 superimposed upon the third unit in Figure 7, the projecting end portion of the third tie rod section is presented above the fourth unit. With this construction the shoe and all four of the units may be assembled above 75 the ground and directed into the bore of the well after which the operation of connecting additional tie rod sections to those already arranged between the sections of the units may be carried out any time when assembling additional units and the lowering 80 of the casing into the bore of the well.

The depressions for the dowels are indicated by 44 in Figure 11, and it is to be noted that the presence of the dowels as there shown, operates to prevent lateral displacement of the sections of the units when these are assembled. It is to be noted that the foregoing is descriptive of a structure which is simple and comparatively inexpensive and efficient for effecting the lowering of a relatively long casing made up of the units shown in Figure 7 into a relatively deep well. It is to be noted that all of the tie rod sections are provided with openings 39 and 42 which will permit of the use of the dowels for the purposes described.

90 The ducts or water passages 45 of the sections 37 and 38 correspond to the ducts in the other forms of the invention and are 100 adapted for containing filtering material such as pebbles.

95 For additionally locking the unit in all forms of the invention against lateral displacement, suitable dowels 46 may be employed and arranged in the upper sides of the sections so as to enter openings in the lower sides of the sections immediately thereabove, and additional dowels may be arranged in the ends of one of the sections 105 as shown at 47 so as to enter openings in the ends of the opposite section, all of which is 110 shown in Figures 2 and 4.

115 Although I have shown and described one embodiment of my invention, it is to be understood that the same is susceptible of various changes; and I reserve the right of employ such as may come within the scope of the appended claims.

120 I claim:

1. In a device of the type described, a well casing formed of a plurality of sections, each section having a longitudinally extending duct disposed between the inner and outer walls and having grooves in the top and bottom edges, the top groove extending inwardly from the duct to the inner wall, while its bottom groove extends outwardly from the duct to the outer wall.

125 2. In a device of the type described, a sec-

130

tional wall casing, each section being composed of a plurality of arcuate segments, each segment having a duct therein extending between the outer and inner wall of the segment, and having a groove in the upper and lower edges of each segment, the upper groove extending inwardly from the duct to the inner surface of the segment and the bottom groove extending outwardly from the duct to the outer surface, the segments of the adjacent sections covering the grooves for forming passageways connecting with the ducts.

3. A device of the type described comprising a perforated wall casing made up of a plurality of sections and bearing against the wall of the well, a sectional casing mounted inside of and spaced from the perforated casing, filtering means disposed in the space between the two casings, the sectional casing being provided with water conveying ducts and filtering means disposed in said ducts.

4. A device of the type described comprising a sectional perforated casing, a second sectional casing enclosing said first named casing and being spaced therefrom, water

conveying ducts disposed in the second casing and filtering means disposed in said ducts and in the space between said casings.

5. In a device of the type described a sectional casing, each section being composed of segments, fastening members connecting the segments of each section to segments of adjacent sections, said members comprising strips, dowel pins connecting said strips together, said segments having recesses for receiving said dowel pins whereby said sections are supported one upon the other.

6. In a device of the type described a sectional casing, each section being composed of segments, fastening members connecting the segments of each section to segments of adjacent sections, said members comprising strips, dowel pins connecting said strips together, said segments having recesses for receiving said dowel pins whereby said sections are supported one upon the other, certain of said strips projecting beneath the lowermost section and a casing for supporting the lowermost section being secured to the projecting portion of said strip.

ADOLPH PAULSEN.
